UNITED STATES PATENT OFFICE.

CLIFTON ALVADO FARON, OF LOS ANGELES, CALIFORNIA.

RAILWAY.

1,090,140.

Specification of Letters Patent. Patented Mar. 17, 1914

Application filed January 13, 1913. Serial No. 741,876.

To all whom it may concern:

Be it known that I, CLIFTON ALVADO FARON, a citizen of the United States, residing at 431 Court street, Los Angeles, in the county of Los Angeles and State of California, have invented a new and useful Improvement in Railways, of which the following is a specification.

This invention relates to railways, and more particularly to railway roadways and the elements thereof, and to certain features to be applied to the rolling stock and coöperating with the roadway elements; and it has for its general object to provide improvements in railways of the general character stated whereby the rolling stock is stabilized upon the roadway and prevented from leaving the rails thereof.

In practising the invention, I provide a particular formation and construction of parts and features entering into the roadbed equipment, and further provide particular elements or a particular element coöperating therewith and carried by or connected with the rolling stock, all such features coöperating to prevent the rolling stock from leaving the rails due to either lateral or vertical displacement, or both such lateral and vertical displacement combined. In one embodiment of the invention, these additional and particular features of roadbed organization are attached directly to the rails; and further embodiment of the invention may include the provision of such elements in or upon the roadway and installed independently with respect to the rails.

The invention has for further objects the provision of improvements in rails of the general character stated which will be superior in point of relative simplicity and inexpensiveness of construction, combined with positiveness in service, durability and capability of resistance to heavy strains tending to displace the rolling stock, which may be conveniently installed and removed from position of service, and which will be generally superior in reliability and efficiency.

With the above and other objects in view, the invention consists in the novel and useful provision, formation, construction, combination, association and relative arrangement of parts, members and features, all as

hereinafter described, shown in the drawing and finally pointed out in claims.

In the drawing: Figure 1 is a transverse sectional view of a portion of a railway roadbed illustrating the invention applied to the same; Fig. 2 is a perspective view of a rail element constituting a leading feature of the invention; Fig. 3 is a similar view of supporting means for the rail element shown in Fig. 2; Fig. 4 is a view of the rail element and supporting means therefor applied to a portion of a standard traction rail; Fig. 5 is a similar view of the same construction as shown in Fig. 4 applied to an auxiliary support installed in the roadbed and beneath the traction rail; Fig. 6 is a similar view of the same features shown as applied to a further auxiliary support installed in the roadbed and laterally of the adjacent traction rail; and Fig. 7 is an edge view of one of the wheel elements shown in Fig. 1 as coöperating with the novel rail element shown in said figure. The showing in Figs. 2 to 7 inclusive is shown on an enlarged scale, the subjects of such figures being detached views of features of the invention shown in assemblage or in installation in Fig. 1.

Corresponding parts in all the figures are designated by the same reference characters.

Referring with particularity to the drawing, A designates the roadbed proper of a railway, the invention being shown as applied thereto both in connection with the ordinary traction rails B and auxiliary supports C and H which are disposed beneath the plane of the bases of the traction rails B.

D designates the rail element constituting an essential feature of the invention, and E in each instance designates a wheel element which coöperates with such rail element.

F in each instance designates the supporting means for the rail element, the same being directly connected with the traction rails B or with the auxiliary supports C and H. The supporting means F, in one preferred form, comprises a body plate 8 perforated as at 9 to accommodate bolts for applying the same to the rails or auxiliary supports. Web 10 projects centrally from the body plate 8 and is bifurcated to produce a cavity or recess 11 within which fits the rail element D. At the outer ends of

the furcations of the web 10 are formed transverse angular flanges 12 which are arranged in parallelism and spaced apart, each being perforated, as at 14, for the reception 5 of bolts or like securing means. The rail element D comprises an elongated angular body 15, of standard rail length or other suitable dimensions, which is applied to and connected with a plurality of the supporting 10 means F, the same comprising a central plane portion 15^a from which spring divergent plane portions 15^b terminating in oppositely directed flanges 15^c, the inner faces of the body portion 15 being bevelled off where the flanges 15^c join the divergent portions 15^b as at 15^d. The formation of the recess or cavity 11 in each of the holding 15 means F is complementary to the formation of the rail element D, so that the rail element 20 exactly fits within the same, the flanges 15^c being received by the angular flanges 12, and being bolted thereto through eyes 16 in the flanges 15^c and through eyes 17 in the flanges 12.

25 The wheel elements E which coöperates with the rail elements D are shown, as having the usual circular tread portions 19 which engage with the inner faces of the rail portions 15^a. The wheels are of increasing 30 thickness inwardly from the treads, as at 18, for a pre-determined distance, such formation merging into plane central portions of wheel centers 20.

Referring to Fig. 1, the supporting means 35 F are shown as applied by the body plates 8 to the webs of the standard traction rails B shown therein. It will be understood that a continuous series of such rail elements D are applied to both of the continuous series 40 of traction rails B, whereby such rail elements project inwardly from the web of the traction rails in opposition for the reception of the wheel elements E; the latter being shown in Fig. 1 as applied thereto in 45 couples, one for each series of rail elements D, each of such couples being conveniently connected and held in proper relation to each other and to the rail elements D by a truck K of any preferred and suitable form.

50 The supports C are shown as consisting of I beams or the like, installed within the roadbed, directly beneath the traction rails B, and bolted to metallic ties or the like 21 resting upon the surface of the roadbed 55 proper and in turn supporting the traction rails B. To these supports C the supporting means F are shown as applied, at the outer faces of such supports, the rail elements D being in turn applied to such supporting 60 means F in two continuous series. The ties 21 are shown as constituting the auxiliary supports H; and to such auxiliary supports, laterally and outwardly of the supports C, are applied continuous series of the supporting 65 means F, together with the attached rail

elements D. The rail elements thus supported by the auxiliary support H will face downwardly or at right angles with the facing directions of the element or elements carried by the auxiliary supports C. Other 70 wheel elements E may be applied to the rail elements D supported by the supports C and auxiliary supports H, the axis of these wheel elements being in rectangular relation.

Brace plates G may be applied to the traction rails B so as to overlap the base flanges of such rails, such brace plates being bolted to the ties 21 and extending in continuous series, one such series laterally and outwardly of each traction rail B. These brace 80 plates G add stability to the traction rails and continue to counteract strains imposed upon the traction rails in the use of the invention.

The operation, method of use and advantages of my improvements in railways will be readily understood from the foregoing description taken in connection with the accompanying drawing and following statement.

The truck K may be directly connected with and carried by the truck of the car or other rolling stock the traction wheels of which are applied to the traction rails B in the usual manner. The wheel elements E 90 which coöperate with the rail elements D applied to the supports C and auxiliary supports H, may be connected up with the rolling stock in any preferred and suitable manner. The roadbed proper A is, of 100 course, chambered out suitably to accommodate the installation of such latter rail elements and to accommodate the wheel elements E which coöperate with the same, as well as the means of connection between 105 such latter wheel elements and the rolling stock. The rolling stock is not shown in the drawing, as the invention does not contemplate any change or alteration in such rolling stock *per se* but only inserts additional 110 features applicable to and coöperating with the rolling stock for the purpose of stabilizing the same and preventing displacement of the same from the rails.

The circular treads 19 of the wheel elements engage with the inner faces of the plane portions 15^a of the rail elements, so as to limit motion in the direction opposed by such contact. With respect to the wheel elements carried by the truck K, this opposition is to lateral or horizontal play. With respect to the wheel elements coöperating with the rail elements carried by the auxiliary support H, this opposition is to vertical play; and with respect to the wheel elements coöperating with the rail elements carried by the support C this opposition is to lateral play. The flaring wheel bodies between the treads and wheel centers 20 have inclined surfaces which coöperate with the 130

divergent plane faces of the rail element portions 15^b. This engagement is not a binding engagement but loose enough in nature so that the wheels may turn without serious frictional retardation. This engagement opposes play of the wheel and of the rolling stock connected therewith in a direction at right angles to the play which is opposed by the contact of the tread of the wheel with the portion 15^a of the rail element.

It will be understood that under many circumstances and working conditions it will not be necessary to utilize the several series of rail elements D applied to the roadbed as shown in Fig. 1. Under ordinary circumstances the office of the rail elements in connection with the webs of the traction rails B together with the coöperating wheels E, will be sufficient to satisfactorily stabilize the rolling stock and prevent the wheels thereof from leaving the traction rails. The addition of the other series of rail elements D in connection with the supports C and auxiliary supports H, one or both, may be found advisable and advantageous under certain conditions. And, furthermore, this arrangement may, if preferred, be substituted for the arrangement and provision of the rail elements D applied to the traction rails B, or any one of the three methods of installation of the traction rails may be employed independently of the other two.

The wheel elements E do not constitute load-carrying wheels, although it is manifest that they would still serve the purpose of the invention should a part of the rolling stock load be imposed upon them. Their chief function is to coöperate with the rail elements D, in accordance with the arrangement and provision of parts and installations best adapted to the conditions of service to be considered, for the purpose of stabilizing the rolling stock and prevent displacement of the wheels thereof from the traction rails B to which a major portion of the load is applied.

The angular formation of the flanges 12 of the supporting means F serves to retain the rail elements D positively in proper seated position in the recesses or cavities 11, overcoming any tendency of the rail elements to creep or become displaced or move relatively to the supporting means. This effect of course is enhanced by the positive bolting of the rail elements to the supporting means; and likewise, all of the several rail elements, supporting means, supports, auxiliary supports and traction rails and brace plates are, as shown, positively bolted together in rigid relation in accordance with standard practice.

The beveled formation at 15^a of the angular bodies 15 of the rail elements D produces a greater divergence between these

faces than between the inner faces of the portions 15^b of the rail element bodies, and thus facilitates the entrance of the wheel elements E to their working positions in connection with the rails.

70

I do not desire that my invention be so construed as to limit it to the particular details of formation and construction herein set forth and shown in the drawing, such aspects of the invention being subject to wide variations within the true spirit of the invention.

Having thus described my invention, I claim and desire to secure by Letters Patent:

1. A railway roadbed provided with the usual traction rails and with two series of rail elements in addition thereto, and wheel elements for application to rolling stock and adapted to coöperate with said series of rail elements to prevent displacement of the wheels of the rolling stock from the traction rails; said rail elements comprising angular bodies having wheel-tread-receiving plane portions and divergent plane portions projecting therefrom and adapted to embrace the wheels.

2. A railway roadbed provided with the usual traction rails and with two series of rail elements in addition thereto, and wheel elements for application to rolling stock and adapted to coöperate with said series of rail elements to prevent displacement of the wheels of the rolling stock from the traction rails; said rail elements comprising angular bodies having wheel-tread-receiving plane portions and divergent plane portions projecting therefrom and adapted to embrace the wheels; and supporting means for the rail elements comprising each a body plate and a recessed web projecting therefrom and receiving the angular rail element body.

3. A railway roadbed provided with the usual traction rails and with two series of rail elements in addition thereto, and wheel elements for application to rolling stock and adapted to coöperate with said series of rail elements to prevent displacement of the wheels of the rolling stock from the traction rails; said rail elements comprising angular bodies having wheel-tread-receiving plane portions and divergent plane portions projecting therefrom and adapted to embrace the wheels; and supporting means for the rail elements comprising each a body plate and a recessed web projecting therefrom and receiving the angular rail element body; each of said webs having spaced angular flanges, and said rail elements having oppositely directed flanges which are received by and connected with said angular flanges.

4. A railway roadbed provided with the usual traction rails, rail elements applied to the traction rails in opposed relation and between the traction rails, and other rail ele-

130

ments applied to the roadbed independently of the traction rails; each of said rail elements being formed for engagement by a wheel element for application to rolling stock traversing the traction rails to hold the wheels of the rolling stock to the traction rails.

5. A railway roadbed provided with the usual traction rails, rail elements applied to the traction rails in opposed relation and between the traction rails, and other rail elements applied to the roadbed independ-

ently of the traction rails; each of said rail elements being formed for engagement by a wheel element for application to rolling stock traversing the traction rails to hold the wheels of the rolling stock to the traction rails; each of said rail elements being formed to opposed play of the said wheel elements in two directions. 15
